APPLIANCE FOR USE IN SHARPENING OR
RESHARPENING SAFETY-RAZOR BLADES

Alfred Leonard Walton, Blackpool, England

Application July 13, 1951, Serial No. 236,489
In Great Britain January 25, 1951

3 Claims. (Cl. 51—81)

1

The present invention relates to appliances for sharpening or re-sharpening safety razor blades.

In my prior U. S. Patent No. 2,549,148, dated April 17, 1951, I have described an appliance which is hand operated by a reciprocal movement over and pressure upon a relatively stationary surface, and comprises at least two spaced sharpening rollers upon the curved surfaces of which the cutting edges of the blade can be brought to bear, and a driving roller mounted in slotted bearings so that, when rotated in one direction by contact with the said relatively stationary surface, it will move into engagement with one of the sharpening rollers and cause rotation of this roller in a direction away from the edge of the blade in contact with this roller and, when rotated in the opposite direction by contact with the relatively stationary surface, it will move into engagement with the other sharpening roller and cause rotation of this other roller in a direction away from the edge of the blade in contact with this roller.

One of the objects of the present invention is to provide an appliance suitable for use in sharpening or re-sharpening a single-edged blade from one side at a time.

To this end the appliance comprises a frame, a seating on the frame for the blade to be sharpened, a sharpening roller mounted for rotation in a fixed position on the frame and so located that when the blade is applied to the seating one side of the cutting edge of the latter will bear on the curved surface of the said roller, and a driving roller mounted in slotted bearings in the frame so that, when the appliance is moved in one direction over a stationary surface, such as a table-top, with the driving roller in contact with this surface, the sharpening roller will be caused to rotate in a direction resulting in movement thereof into engagement with the sharpening roller with consequent rotation of the sharpening roller in a direction away from the cutting edge of the blade, while, when the appliance is moved in the opposite direction over the said surface, the driving roller will move out of engagement with the sharpening roller so that rotation of the latter will cease.

The appliance may include a casing which engages slidably and removably over the frame and is so formed that it can be used to apply pressure to the blade so as to hold the latter firmly down on its seating during the sharpening operation.

The casing may also be so formed that it can be used to apply pressure to the blade at a point

2

intermediate its cutting edge and back edge, thereby maintaining the cutting edge in contact with the curved surface of the sharpening roller with the requisite degree of pressure.

Another object of the present invention is to provide an appliance suitable for use in sharpening or re-sharpening a single-edged blade from both sides at the same time.

To this end the appliance comprises a frame, a casing engaging slidably and removably over the frame, a seating on the frame for the blade to be sharpened, a sharpening roller mounted for rotation in a fixed position on the frame and so located that, when the blade is applied to the seating, one side of the cutting edge of the blade will bear on the curved surface of the said roller, a sharpening roller mounted for rotation in a fixed position in the casing and so located that, when the casing is applied to the frame, the said roller will have surface contact with the sharpening roller on the frame and will also bear on the other side of the cutting edge of the blade, the cutting edge being thereby engaged in the nip between the two rollers, and a driving roller mounted in slotted bearings in the frame so that, when the appliance is moved in one direction over a stationary surface, such as a table-top, with the driving roller in contact with this surface, the sharpening roller will be caused to rotate in a direction resulting in movement thereof into engagement with the sharpening roller on the frame with consequent rotation of this roller and of the sharpening roller on the casing in a direction away from the cutting edge of the blade, while, when the appliance is moved in the opposite direction over the said surface, the driving roller will move out of engagement with the sharpening roller on the frame so that rotation of this roller and of the sharpening roller on the casing will cease.

In the arrangement described and illustrated in my prior patent referred to above the appliance is designed to act on both sides of the two cutting edges of a double-edge blade simultaneously. For this purpose, the appliance has two pairs of sharpening rollers, one roller of each pair being carried by a frame and the other roller of the pair being carried by a casing fitting over the frame, and there is employed a driving roller carried by the frame and movable into engagement with the one or the other sharpening roller of the frame.

A further object of the present invention is to provide an appliance suitable for use in sharpening or re-sharpening the two edges of a

double-edged blade from one side only at the same time.

To this end the appliance comprises a frame, means on the frame for locating the blade to be sharpened, two spaced sharpening rollers supported for rotation in fixed positions on the frame and so located that, when the blade is applied to the locating means, the cutting edges of the blade will bear by one side on the curved surfaces of the respective sharpening rollers, and a driving roller mounted in slotted bearings in the frame so that, when the appliance is reciprocated over a stationary surface, such as a table-top, with the driving roller in contact with this surface, the roller will be caused to rotate firstly in a direction resulting in movement thereof into engagement with one of the sharpening rollers with consequent rotation of this roller in a direction away from the corresponding cutting edge of the blade, and secondly in a direction to bring the driving roller out of engagement with the first-mentioned sharpening roller and into engagement with the other sharpening roller with consequent rotation of this roller in a direction also away from the corresponding cutting edge of the blade.

The construction just explained may include a casing engaging slidably and removably over the frame and so designed that it can be used to flex the blade for the purpose of maintaining the cutting edges of the blade in pressure-contact with the sharpening rollers.

The construction of the casing may, furthermore be such that the pressure-contact of the cutting edges of the blade with the sharpening rollers is limited to avoid excessive pressure being applied.

In another construction of the casing, the latter is fitted with resilient pads which serve the two-fold purpose of applying even pressure to the blade and frictionally gripping the blade-locating means on the frame when the casing is applied to the frame and is pressed downwardly.

Reference is now made to the accompanying drawings which contain five figures, marked 1 to 5, illustrating in cross-section the appliance when constructed according to five varying forms respectively.

The construction according to Figure 1 is designed for sharpening or re-sharpening, from one side only at a time, a single-edge blade. To this end the construction consists of a rectangular frame 1 carrying a single sharpening roller 2. The roller is mounted for rotation in a fixed position in the frame and is arranged nearer one end wall of the frame than the other end wall, the roller being of such diameter that its upper part projects above the frame.

The upper edge of the frame is formed with a seating 3 adapted to receive and locate the thickened back edge portion of a single-edged blade 4, the seating being so positioned relatively to the roller 2 that when the back edge portion of the blade is engaged therein, the cutting edge of the blade will bear by one of its sides on the top of the curved surface of the roller.

The side walls of the frame 1 are formed with depending lugs 5 in each of which there is provided a slot 6 extending horizontally. The end portions of a spindle 7 engage freely in these slots 6, and a driving roller 8 is secured around the spindle. The axis of the driving roller 8 lies below the axis of the sharpening roller 2 and the driving roller is of such diameter that its lower part projects below the lugs 5 and move-

ment of its spindle 7 along the slots 6 towards the sharpening roller 2 will cause the driving roller to come into surface-contact with the sharpening roller.

The construction now being described includes a box-like casing 9 with an open base, the casing fitting slidably and removably over the frame 1. The casing is formed interiorly with two depending webs 10 and 11. After the blade 4 has been applied to the frame 1 in the manner described, in the absence of the casing 9, and the casing is now applied to the frame and pressed downwardly, the web 10 will bear on the thickened back edge portion of the blade so as to hold this portion in the seating 3, while the web 11 will apply a degree of pressure to a part of the blade situated near the cutting edge, thereby maintaining one side of the cutting edge in close contact with the sharpening roller 2.

To perform a sharpening operation, the assembled appliance with the blade 4 in position is applied to a flat surface, such as a table-top, with the exposed part of the driving roller 8 resting on the said surface. By now moving the appliance in the direction of the arrow *a*, the driving roller 8 will be rotated in the direction of the arrow *b* and at the same time will move into surface-contact with the sharpening roller 2, thereby rotating the roller 2 in the direction of the arrow *c*, that is to say, in a direction away from the cutting edge of the blade. When the appliance is moved in the opposite direction, the driving roller will be caused to move out of contact with the sharpening roller so that rotation of the latter will cease. Hence, during movement of the appliance to-and-fro over the flat surface, the sharpening roller can only be rotated in a direction away from the cutting edge of the blade.

When one side of the cutting edge of the blade has been sharpened, the casing 9 is removed, the blade 4 turned over, the casing replaced, and the sharpening operation repeated for the other side of the cutting edge.

The construction according to Figure 2 is designed for sharpening or re-sharpening the cutting edge of a single-edged blade from both sides at the same time, thereby avoiding the necessity for turning over the blade to complete the sharpening operation.

In this construction, the frame and its associated parts are of the same form as those in the arrangement according to Figure 1, and like parts bear like reference characters to avoid repetition of description.

As before, the construction includes a box-like casing 9 fitting slidably and removably over the frame 1, the casing being formed with a depending web 10 adapted to bear on the back edge portion of the blade 4. In the present instance, instead of the casing having a second depending web, it is provided with a sharpening roller 12 which is of the same diameter as the sharpening roller 2 and which, with the casing fitted over the frame, lies directly above and has surface contact with the roller 2, the cutting edge of the blade (when present) then being engaged in the nip between the two rollers 2 and 12 so that the roller 2 has contact with one side of the cutting edge, while the roller 12 has contact with the other side.

The construction according to Figure 2 works in much the same way as that according to Figure 1, as will be apparent from a consideration of the arrows *a*, *b* and *c*. In this instance, however,

rotation of the sharpening roller 2 will cause rotation of the sharpening roller 12 and from this it follows that, as the roller 2 is rotatable only in a direction away from the cutting edge of the blade, so is the roller 12 rotatable only in a direction away from the cutting edge as indicated by the arrow *d*, the combined rotation of both rollers resulting in both sides of the cutting edge being sharpened simultaneously.

The construction according to Figure 3 is suitable for use in sharpening the two cutting edges of a double-edged blade from one side only at the one time.

In this construction, as before, the frame 1 has lugs 5 containing slots 6 in which are freely engaged the end portions of a spindle 7 fitted with a driving roller 8. In other respects the frame differs. It is provided with two spaced sharpening rollers 13 and 14 which are of equal size and are arranged one on either side of the driving roller 8, the distance between the axes of these sharpening rollers being the same as or slightly greater than the width of the blade 15 to be sharpened. The diameter of the sharpening rollers in comparison with the diameter of the driving roller 8 and the length of the slots 6 is such that the driving roller can have contact with either the roller 13 or the roller 14, but not with both at the same time.

The upper edge of the frame 1 is formed with a cross-bar 16 which is arranged midway between the sharpening rollers 13 and 14 and the upper surface of which forms a seating for the blade 15, this upper surface being so located that it lies in a plane slightly below a plane joining the upper extremities of the curved surfaces of the sharpening rollers. The cross-bar carries upwardly projecting pins 17 adapted to pass through the usual holes in the blade so as to locate the latter on the cross-bar, with the cutting edges of the blade resting on the upper part of the curved surfaces of the rollers 13 and 14.

The appliance according to Figure 3 includes a box-like casing 9 fitting slidably and removably over the frame 1. The casing has clearance holes 18 through which the pins 17 project when the casing is applied to the frame. The casing is also formed interiorly with downwardly extending webs 19 adapted to bear on the blade at points situated near the cutting edges of the latter so as to press the undersides of the cutting edges of the blade against the curved surfaces of the sharpening rollers 13 and 14, such pressure also resulting in the blade being held down firmly on the cross-bar 16.

When, in the absence of the casing 9, a blade is engaged over the pins 17 and the casing is then replaced, the sharpening operation is performed by reciprocating the appliance over a flat surface in the manner explained with reference to the preceding figures. Under these conditions, when the appliance is moved to the right in the figure, the driving roller 8 will be rotated clockwise and at the same time will move bodily into contact with the sharpening roller 13, causing this roller to be rotated anti-clockwise, that is to say, in a direction away from the edge of the blade in contact with the roller 13. When the appliance is moved to the left, the driving roller 8 will be rotated anti-clockwise and at the same time move out of contact with the sharpening roller 13 and into engagement with the sharpening roller 14. Hence, rotation of the roller 13 will cease while the roller 14 will be rotated clockwise, that is to say, in a direction away from the corresponding

cutting edge of the blade. In other words, during the sharpening operation, both sharpening rollers will be rotated in directions which are always away from the cutting edges of the blade.

5 When one side of the cutting edge has been sharpened, the other side can be sharpened by removing the casing 9, turning the blade over, replacing the casing and reciprocating the appliance over the flat surface once again.

10 The construction illustrated in Figure 4 has much in common with that according to Figure 3 and similar parts are identified by the same reference numerals. In this instance, however, the sharpening rollers 13 and 14 are made a little larger in diameter so that the upper parts of their curved surfaces project in a more pronounced fashion above the upper surface of the cross-bar 16. The diameter of the driving roller 8 is correspondingly reduced to compensate for the increased diameter of the sharpening rollers.

15 In Figure 4 the casing 9, which is again of box-like form and fits slidably over the frame 1, is formed with bushes 20 which project downwardly from the top part of the casing and fit freely over the blade-locating pins 17 on the cross-bar 16, the lower ends of the bushes being adapted to bear on the portion of the blade 15 which is situated directly above the cross-bar. With this arrangement, when downward pressure is applied to the casing 9, the blade will be flexed downwardly to maintain its cutting edges pressed against the sharpening roller, the amount of pressure exerted on the blade in this fashion being positively limited by the pinching of the central part of the blade between the upper surface of the cross-bar and the lower ends of the bushes 20. Thus the degree of pressure-contact of the cutting edges of the blade on the sharpening rollers can never be excessive.

20 The construction according to Figure 5 is, in many respects, the same as that of Figure 3, similar parts being marked with similar reference numerals. The main purpose of Figure 5 is to illustrate a distinct variation in the form of the casing 9.

25 In Figure 5 the casing is again of box-like form adapted to fit slidably and detachably over the frame 1. In this instance, however, instead of the casing being formed with clearance holes for the blade-locating pins 17, it is provided interiorly with a pair of pads 21 of rubber or other suitable resilient material, which are arranged close together and extend in the direction of the length of the cross-bar 16. The pads are substantially of reclining S-shape in cross-section and are held in the upper part of the casing by means of bars 22.

30 When the casing 9 is applied over the frame 1 and is pressed downwardly, the pins 17 will engage between the pads and will be frictionally gripped by the latter, the casing being thereby retained in engagement with the frame when the appliance is in use. At the same time, portions of the pad will bear resiliently on parts of the blade lying on each side of the locating pins 17 and thus apply even pressure to the blade in a downward direction so as to maintain the cutting edges in contact with the sharpening rollers 13 and 14 when the appliance is in use.

35 70 I claim:

1. An appliance for use in sharpening or re-sharpening safety-razor blades comprising a frame, two sharpening rollers rotatably supported in said frame and disposed in spaced parallel relationship, a cross bar on said frame dis-

posed midway between said sharpening rollers, said bar being adapted to provide a seating for the blade to be sharpened which seating is disposed in a plane slightly below that joining the upper extremities of the curved surfaces of the sharpening rollers, projecting pins on said bar for locating the blade with respect to the latter, a driving roller mounted in slotted bearings in the frame so that dependent upon the direction of movement of the latter, said driving roller will be moved into driving relationship with one or other of said sharpening rollers, a casing adapted slidably to engage over the frame, and resilient means carried by said casing and adapted on application of the latter to said frame to apply an even pressure to any blade positioned on the cross bar and also frictionally to grip the projecting pins carried by said cross bar, the construction being such that with a blade positioned in the frame and the casing applied to the latter when the appliance is reciprocated over a stationary surface with the driving roller in contact with the latter, said roller will be caused to rotate firstly in a direction resulting in movement thereof into engagement with one of the sharpening rollers with consequent rotation of this roller in a direction away from the corresponding cutting edge of the blade, and secondly in a direction to bring the driving roller out of engagement with the first-mentioned sharpening roller and into engagement with the other sharpening roller with a consequent rotation of this roller in a direction also away from the corresponding cutting edge of the blade.

2. An appliance for use in sharpening or re-sharpening safety-razor blades comprising a frame, two sharpening rollers rotatably supported in said frame and disposed in spaced parallel relationship, a cross bar on said frame disposed midway between said sharpening rollers, said bar being adapted to provide a seating for the blade to be sharpened which seating is disposed in a plane slightly below that joining the upper extremities of the curved surfaces of the sharpening rollers, projecting pins on said bar for locating the blade with respect to the latter,

a driving roller mounted in slotted bearings in the frame so that dependent upon the direction of movement of the latter, said driving roller will be moved into driving relationship with one or other of said sharpening rollers, a casing adapted slidably to engage over the frame, and two pads of resilient material affixed in spaced parallel relationship to the inner surface of said casing and adapted on application of the latter to said frame to apply an even pressure to any blade positioned on the cross bar and also frictionally to grip the projecting pins carried by said cross bar, the construction being such that with a blade positioned in the frame and the casing applied to the latter when the appliance is reciprocated over a stationary surface with the driving roller in contact with the latter, said roller will be caused to rotate firstly in a direction resulting in movement thereof into engagement with one of the sharpening rollers with consequent rotation of this roller in a direction away from the corresponding cutting edge of the blade, and secondly in a direction to bring the driving roller out of engagement with the first-mentioned sharpening roller and into engagement with the other sharpening roller with a consequent rotation of this roller in a direction also away from the corresponding cutting edge of the blade.

3. An appliance for use in sharpening or re-sharpening safety-razor blades as claimed in claim 2 wherein the pads of resilient material comprise strips substantially of reclining S-shape in cross section.
